CIRCUIT BREAKER

John E. MacNeill, Wilkinsburg, Pa., assignor to
 Westinghouse Electric & Manufacturing Company,
 East Pittsburgh, Pa., a corporation of
 Pennsylvania

Application April 30, 1937, Serial No. 139,921

30 Claims. (Cl. 200—145)

The invention relates to switchgear apparatus in general and more particularly to circuit breakers for controlling high voltage transmission systems.

5 It has heretofore been the usual practice, in the case of large capacity circuit breakers, to enclose the relatively movable contacts and other related parts in a metal tank. Large insulator bushings were necessary to insulate the terminals of the breaker from the metal tank; and the tank itself had to be of large dimensions in order to provide sufficient space between the tank and all of the live parts. In high capacity breakers of this type, the metal tank occupies considerable 10 space and requires a very large quantity of oil for insulation purposes. The large amount of oil required constitutes a dangerous fire hazard due to the fact that it may be ignited on short circuit or on surges due to lightning flashes or 15 other causes.

It has been proposed to use casings of vitreous insulating material in place of the metal tank in order to reduce the space occupied and the amount of oil required by the breaker. Such an 20 arrangement is usually referred to as a porcelain clad oil-poor circuit breaker. Circuit breakers of this type are of more or less recent development and much is yet to be desired in the way of a satisfactory structure. The present invention 25 relates to circuit breakers of this type and one object of the invention is the provision of an improved porcelain clad circuit breaker capable of controlling and interrupting extremely large amounts of electric power, which is simple, 30 safe and reliable in operation and relatively inexpensive to manufacture and service.

Another object of the invention is the provision 35 of an improved circuit breaker in which the contact means, actuating means and other related parts are disposed in tubular insulating casings of relatively small diameter so that the breaker occupies a relatively small amount of space and requires a small quantity of insulating and arc extinguishing liquid.

Another object of the invention is the provision 40 of a circuit breaker having a unitary contact assemblage including a plurality of pairs of relatively movable main contacts and associated arc extinguishing means and a pair of auxiliary separable disconnecting contacts, connected in series 45 and arranged in tandem within a small diameter tubular casing of insulating material for operation by an improved high speed actuating means.

Another object of the invention is the provision 50 of an improved actuating means for operating

the series of tandem arranged pairs of contacts of the breaker which provides maximum travel and speed of operation of the switch member together with high contact pressure when the breaker is closed.

Another object of the invention is the provision 55 of a circuit breaker as previously described in which the contact assemblage is secured to a cap member which is removably mounted in the casing; the improved actuating means being supported by the cap member so that the entire assemblage together with the actuating means may be readily removed with the cap member from the casing for inspection, repairs or 10 replacements.

Another object of the invention is the provision 15 of an improved oil circuit breaker embodying a pair of contact assemblages each including a series of tandem arranged interconnected circuit controlling arc extinguishing units mounted in the upper sections of a pair of hollow cylindrical insulator columns and connected by a series connector bridged between the two columns, the arrangement of the current path through the breaker being such as to provide more nearly 20 equal voltage distribution between the several units, and in many cases eliminating the necessity of providing separate condenser shielding means for this purpose.

Another object of the invention is the provision 25 of an improved circuit breaker, as previously described, in which the lower sections of the insulator columns provide space for current transformers and potential dividers thus eliminating the necessity of separate containers and insulator 30 bushings for these devices.

Another object of the invention is the provision 35 of a circuit breaker embodying a casing of strong insulating material for enclosing and supporting a contact assemblage including at least 40 one pair of relatively movable contacts and actuating means therefor, and an outer weatherproof housing of vitreous insulating material surrounding and protecting said casing; so that in the event of breakage of the outer housing the circuit 45 breaker remains completely operative.

In carrying out the invention, two hollow cylindrical columns of vitreous insulating material replace the metal tank formerly used. The lower portions of the columns serve to elevate and insulate the live parts from ground and to provide 50 containers for current transformers and potential dividers to be used for relaying and indicating purposes. The upper portion of each column forms an interrupting section which con- 55

tains a unitary removable contact assemblage comprising a plurality of interconnected circuit controlling arc extinguishing units arranged in tandem, the relatively movable contacts of which are connected in series. The series of connected arc extinguishing units are connected with line terminals located at the base of the interrupting sections and with a series connector bridged between the top of the two columns.

10 The novel features that are considered characteristic of the invention are set forth in particular in the appended claims. The invention itself, however, both as to structure and operation, together with additional objects and advantages thereof will best be understood from the following detailed description of one embodiment thereof when read in connection with the accompanying drawings, in which

Figure 1 is a front elevational view of an arrangement for mounting a plurality of single pole circuit breaker units constructed in accordance with the present invention, for gang operation to form a multi-pole breaker assembly.

Fig. 2 is an enlarged side elevational view, partly in section of one of the individual single pole circuit breaker units embodying the features of the invention;

Fig. 3 is an enlarged elevational view partly in section of a portion of one of the unitary contact assemblages;

Fig. 4 is a view similar to Fig. 3 taken at right angles thereto showing the parts of the contact assemblage in the closed-circuit position of the breaker;

Fig. 5 is a view similar to Fig. 4 showing the parts of the contact assemblage in the open-circuit position of the breaker; and,

Fig. 6 is an enlarged elevational view, partly in section of an interrupting section of the circuit breaker.

Referring to the drawings, and particularly to Fig. 2 thereof, the single pole circuit breaker unit illustrated is provided with a supporting base 7 of the truck type having a pair of rollers 9 at each end thereof to facilitate moving the breaker unit into and out of position. A pair of vertically arranged hollow columns 11 and 13 of vitreous insulating material, such as porcelain or the like, are mounted in spaced relation on the base 7, one adjacent each end thereof. The columns may consist of a single piece of vitreous insulating material or they may be made up of several sections 15, 17 and 19 secured end to end, as shown in Fig. 2. The several sections are clamped together and the whole column clamped to the base 7, in any suitable manner, preferably in such a manner that only compressive stresses are applied to the columns.

A tube 21 of insulating material compounded from fibrous material impregnated with synthetic resin extends concentrically through the lower sections 17 and 19 of each column, while a similar tube 23, also of similar insulating material, extends concentrically through the upper section 15 of the column.

65 A ring member 25 provided with an internal flange 27 (Fig. 6) is rigidly secured to the upper end of each of the inner insulating tubes 23. Each of the ring members 25 has a second internal flange 29 which abuts the upper end of the outer porcelain section 15 of the column.

A unitary contact assemblage, indicated generally at 31, is removably mounted in the upper section 15 of each insulator column. The unitary contact assemblage comprises, in general,

a stack of individual circuit making and breaking units 33 arranged in tandem relation, a movable switch member 35 (Figs. 3 and 4), and an actuating means indicated generally at 37 for the switch member and stack of circuit making and breaking units.

Referring to Figs. 3, 4 and 5, each circuit making and breaking unit 33 comprises, in general, a stationary contact 39, a cooperating movable contact 41 and an associated arc extinguishing means for the contact indicated generally at 43. Any suitable type of arc extinguishing means may be used. One preferred form of arc extinguishing means that may be used is shown and described in detail in the co-pending application of Howard M. Wilcox, Serial No. 83,597, filed June 5, 1936, issued October 12, 1937, as Patent No. 2,095,301 and assigned to the assignee of this invention. Another suitable form of arc extinguishing means that may be used is shown and described in detail in the co-pending application of Roswell C. Van Sickle, Serial No. 83,600, filed June 5, 1936, also assigned to the assignee of this invention.

Each unit 33 has a pair of end plates 45 and a cylindrical shell of insulating material 47.

The several circuit making and breaking units 33 are secured together in spaced stacked relation by means of tie brackets 49, and the pairs of contacts of the several units which will hereinafter be referred to as the main contacts, are connected in series circuit relationship so that during a circuit opening operation, the arc formed incident to the opening of the circuit plays as a series of arcs, which are quickly extinguished by the arc extinguishing means 43 of the several units.

The movable contacts 41 of the several circuit making and breaking units 33 are adapted to be simultaneously actuated by means of a common insulating rod 51 which extends centrally through all of the units, the movable contact 41 of each unit being connected to the rod by means of a pair of levers 53. The levers 53 are pivoted at their one end to fixed brackets 55 secured to the top plate of each unit, the free ends of the levers being connected to the movable contact 41 by means of a pivot pin 57. The intermediate portions of each of the levers 53 is connected to the common actuating rod 51 by means of a pivot pin 59. The levers 53 are each provided with a slot (not shown) for engaging their fixed pivot pin 61 carried by the brackets 55 in order to permit straight line motion of the common actuating rod 51 and the contacts 41. The common actuating rod 51 is biased in an upward direction by means of a suitable compression spring (not shown) so that the movable contacts 41 of the several units 33 are all biased to their open circuit position.

The upper end of the rod 51 has a frictionally engageable female contact 63 secured thereto for cooperation with a movable male contact 65 secured to the lower end of the switch member 35. Any type of spring biased female contact may be used which will resiliently and frictionally grip the cooperating male contact 65. The contact 63 in the actual physical embodiment of the invention has a plurality of circularly arranged fingers (not shown) which are biased inwardly by a coil spring means (not shown) so that they will firmly grip the cooperating male contact 65. The contacts 63 and 65 form what will be referred to as a pair of separable auxiliary disconnecting contacts. The contact 63 is connected by a suitable

shunt conductor (not shown) and by the levers 53 and pins 57 and 59 with the movable contact of the uppermost circuit making and breaking unit 33. A second frictionally engageable female contact 67 (Fig. 6) similar to the contact 63 is secured to the bottom plate of the lowermost circuit making and breaking unit 33, and this contact is electrically connected to the stationary contact 39 of said lowermost unit. The contact member 10 67 serves to connect the units 33 of the stack in circuit with a line terminal in a manner which will be hereinafter described.

The shell 47 of the uppermost circuit making and breaking unit 33 is secured to the lower end 15 of a sleeve 69 of molded insulating material, the upper end of the sleeve being, in turn, secured to a spider casting or cap member 71. The cap member 71 is provided with a pair of oppositely extending integral projections 73 which are 20 adapted to seat on the internal flange 27 of the ring member 25. Suitable bolt fastening means pass through openings provided in the projections 73 and through similar aligned openings provided in the internal flange 27 for securing the cap member 71 in mounted position within the sleeve 25 so that the entire unitary contact assemblage 31 is removably mounted within the insulating tube 23, the stack of circuit making and breaking units being disposed within said insulating tube.

30 The switch member 35 comprises a metallic yoke which is mounted for vertical sliding movement in the insulating sleeve 69 which connects the cap member 71 with the stack of circuit making and breaking units 33. The yoke member 35 is mounted for vertical sliding movement between pairs of guides 75 which are secured by means of rivets 77 to the inner surface of the sleeve 69. The yoke 35 is provided with four rollers 79 which are adapted to roll in grooves provided between 40 the pairs of guides 75. The yoke member 35 with the movable contact 65 secured to the lower end thereof is movable between an open and a closed circuit position to open and close the circuit through the breaker. The closed circuit 45 position of the yoke member is shown in Figs. 3 and 4, and the open circuit position thereof shown in Fig. 5.

It will be seen from the structure thus far described that when the yoke member moves from 50 its closed-circuit position to its open-circuit position, the insulated actuating rod 51 is moved upwardly under the influence of its biasing spring (not shown) to effect simultaneous opening of each pair of main contacts of the several interrupting units. When the movable contacts 41 have reached their full open circuit position, upward movement of the insulating rod 51 ceases. The continued upward movement of the yoke 35 to 55 its open circuit position causes the movable contact 65 to separate from the cooperating stationary contact member 63. The movable contact 65 moves upwardly with the yoke 35 a sufficient distance to introduce a large gap between the contacts 63 and 65 capable of withstanding 60 high voltages. The contacts 63 and 65 thus act in the manner of a disconnecting switch to protect the circuit making and breaking units 33 from surges due to lightning flashes and other causes in the open-circuit position of the breaker. 65 When the movable yoke 35 is moved from the open-circuit position shown in Fig. 5 to the closed-circuit position shown in Fig. 3, substantially the reverse action takes place. The movable contact 70 75 65 is first brought into frictional engagement with its cooperating stationary contact

member 63 carried by the upper end of the insulated actuating rod 51, thus closing the auxiliary disconnecting contacts. Further, downward movement of the yoke member 35 effects downward movement of the actuating rod 51 5 against the force exerted by its biasing spring to cause simultaneous closing of all of the main contacts of the several circuit making and breaking units. During a circuit opening operation, a series of short arcs are formed which are quickly and completely extinguished within the several circuit making and breaking units 33 before the contacts 63 and 65 separate so that no arcing takes place between these last-mentioned contacts.

10 A spider ring 81 (Fig. 2) is mounted between the lower end of the interrupting section 15 and the upper end of the section 47 of each of the hollow insulating columns. The spider ring 81 carries a centrally located conducting stud 83 20 (Fig. 6) which is adapted to be frictionally engaged by the contact member 67 of the lowermost circuit making and breaking unit 33, as shown in Fig. 6. The contact stud 83 is electrically connected with a line terminal connector 85 carried 25 by the spider 81 which extends outside of the insulating column and which serves to connect the breaker in an external circuit. The line terminal connection 85 is insulated from the spider ring 81 by means of an insulating bushing 87. 30 The contact 67 and the conducting stud 83 form a separable electrical connection between the stack of circuit making and breaking units 33 and the line terminal connection 85, which permits the unitary contact assemblies 31 to be 35 readily removed from the insulating tube 23 without necessitating the disconnection of any circuit conductors.

A high speed actuating means indicated generally at 37, Figs. 3, 4 and 5, for the movable 40 switch member 35 is disposed within the cap member 71 and the sleeve 69. The actuating means comprises in general a pair of main driving levers 89, an intermediate multiplying lever 91 and a pair of floating levers 93. The main 45 driving levers 89 are pivotally mounted at their one end on a shaft 95 carried by the cap member 71. The driving levers 89 are connected by a bridging member 96 for simultaneous movement together. The intermediate multiplying 50 lever consists of a yoke shaped member pivoted at one end to a pair of studs 98 formed integral with the cap member 71. Links 101 pivotally connect the outer free ends of the driving levers 89 with a transverse pivot pin 103 bridged 55 between the legs of the intermediate lever 91. The ends of the links 101 engage the transverse pivot pin 103 while the other ends thereof are provided with pivot studs 97 which engage openings provided in the outer ends of the levers 89. 60 The free ends of the legs of the yoke 91 are offset outwardly and are connected to the central portions of the floating levers 93 by means of pivot studs 105, the pivot studs 105 being formed integral with the floating levers 93 and 65 extending through openings provided in the ends of the legs of the intermediate yoke shaped lever 91 and retained in mounted position thereon by means of suitable cotter pins. The ends 107 of the floating levers 93 are pivotally connected 70 to the upper ends of the legs of the movable yoke member 35 by means of pivot pins 109, as best shown in Fig. 3.

The intermediate yoke shaped lever 91 is biased in a counter-clockwise direction about its 75

pivot studs 99 by means of a pair of offset levers 111 which are pivotally mounted on the studs 99. The offset portions 113 of the levers 111 are adapted to engage shoulders formed on the legs of the yoke shaped lever 91. A pair of coiled compressing springs 115 serve to bias the levers 111 in a counter-clockwise direction, the force exerted on the levers 111 being transmitted through the shoulders of the legs of the yoke shaped lever 91 to bias the same in a counter-clockwise direction about its pivot studs 99 to the open circuit position shown in Fig. 5.

The position of the various levers of the actuating mechanism when the breaker is closed are illustrated in Fig. 4. It will be noted that in the closed-circuit position, the lower portion of the floating levers 93, that is to say, that portion from the pivot studs 105 to the pivot pins 109, together with the lower angular portion 20 of the intermediate lever 91, that portion between the transverse pivot pin 103 and the pivot studs 105 form a toggle which is in the "made" position. This toggle in the closed-circuit position of the breaker maintains a high contact pressure between the cooperating contacts of the contact assemblage. In order to break the previously mentioned toggle at the beginning of the circuit opening operation, the intermediate yoke shaped lever 91 is provided with a pair of projections 117 on the opposite sides thereof which are operable at the beginning of the circuit opening operation to thrust the free ends of the floating levers 93 to the right, as viewed in Fig. 4, thus breaking the aforementioned toggle. 35 The cap member 71 is provided with a pair of recesses 119 for receiving pivot studs 120 carried by the free ends of the floating levers 93, during a portion of the movement of said levers, the recesses 119 serve to provide temporary pivot 40 bearings for the studs 120 and the free ends of the levers 93 during certain portions of the movement of the levers. They also permit the levers 93 to move longitudinally in a horizontal direction during portions of the circuit opening 45 and closing operation so that the pivot pins 109 may travel in a vertical line. The various levers of the actuating mechanism thus form a straight line lever mechanism for actuating the switch member 35. The predetermined arrangement 50 of the levers also provides a multiplying action, which multiplies both the travel and the speed of the operation of the switch member 35 over that of the main driving levers 89, as can readily be seen from a comparison of Figs. 55 4 and 5. The switch member 35 and the movable contact 65 carried thereby travel a considerable distance in a vertical direction whereas the main levers 89 move through a relatively small arc to effect such movement of the switch member 35 and contact 65.

The operation of the actuating mechanism is briefly as follows: With the parts of the actuating mechanism in the position shown in Fig. 4 and all of the pairs of contacts closed, let it be 65 assumed that it is desired to open the contacts. The main driving levers are rotated from the position shown in Fig. 4 in a counter-clockwise direction about their shaft 95 to the open-circuit position shown in Fig. 5. At the very beginning 70 of the movement of the driving levers 89, the holding tension exerted by the link 101 on the intermediate yoke shaped lever 91 is relieved and the force exerted by the biasing springs 115 is transmitted through the offset levers 111 to the 75 shoulders 117 of the intermediate lever 91 to

effect counter-clockwise rotation of said lever about the pivot studs 99. During the initial portion of the counter-clockwise movement of the yoke shaped lever 91, the projections 117 thereof engage and move the upper free ends of the floating levers 93 toward the right to break the toggle formed by the lower ends of the lever 91 and the lower portions of the floating levers 93. The driving levers 89 and the intermediate yoke shaped lever 91 both move in a counter-clockwise direction about their fixed pivot axes, the intermediate lever 91 moving at a greater speed due to the fact that the free ends of the levers 89 are pivotally coupled to the transverse pivot pin 103 of the yoke shaped lever 91 which is located a considerable distance from the pivot axis 99 of the intermediate lever. During the counter-clockwise movement of the lever 91, the floating levers 93 are moved both longitudinally and rotatably about their pivot axes 105 from the position 20 shown in Fig. 4 to the position shown in Fig. 5, to effect movement of the yoke shaped switch member 35 from its closed to its open circuit position. The movement of the yoke shaped member 35 from closed to open position effects simultaneous opening of all of the pairs of main contacts 39 and 41 and the auxiliary contacts 63 and 65 in the manner previously described. During the latter part of the circuit opening operation, the studs 120 on the free ends of the floating levers 93 move into the recesses 119 provided to accommodate the same.

During a circuit-closing operation, substantially the reverse action of the actuating mechanism takes place. The driving levers 89 are rotated from the position shown in Fig. 5 in a clockwise direction about their pivot axes to the closed position shown in Fig. 4. Since the free ends of the driving levers 89 are pivotally coupled to the transverse pin 103 of the intermediate lever 91, the lever 91 is also rotated in a clockwise direction about its pivot axis 99 from the position shown in Fig. 5 to the position shown in Fig. 4, with a greater speed and a longer arc however than that of the levers 89. The clockwise movement of the intermediate yoke shaped lever 91 moves the pivot pins 109 from the position shown in Fig. 5 to the position shown in Fig. 4 to effect rotation and bodily movement of the floating levers 93 from the position shown in Fig. 5 to that shown in Fig. 4. This movement of the floating levers drives the switch member 35 from its open-circuit position to its closed-circuit position to effect closing of all of the pairs of contacts in the manner previously described. During the initial portion of the movement of the floating levers to their closed-circuit position, the recesses 119 act as a temporary pivot bearing for the studs 120 so that considerable force is transmitted through the lever mechanism and a high speed closing operation takes place. During the latter part of the movement of the floating levers 93 to their closed circuit position, the toggle formed by the lower portions of the intermediate yoke shaped lever 91 and the floating levers 93 moves into "made" position, as shown in Fig. 4, to secure a high contact pressure between the cooperating contacts of the contact assemblage. The novel arrangement of the various levers of the actuating mechanism provide for a multiplied speed and travel of the switch member 35 over that of the driving levers 89 to secure a maximum travel and speed of operation of the switch member obtainable within the limited diameter of the tubular insulating member 23 and the porcelain column.

An adjustable stop member 122 is threaded through the top of the cap member 11 for limiting counter-clockwise movement of the intermediate yoke shaped lever 91. The stop member 122 may be adjusted to vary the amount of upward travel of the switch member 35 and hence the length of the gap between the contact 65 and the contact 63 in the open position of the breaker. Adjusting screws 116 are also provided in the cap member 11 for changing the tension or force exerted by the biasing springs 115 which tend to open the breaker.

The actuating mechanism 37 in each column of the circuit breaker is operable from outside of the columns by means of a pair of interconnected insulating rods 121 and 123, (Fig. 2) the rods being interconnected by a multiplying lever 125 disposed and pivotally mounted in the spider ring member 31. The upper end of the rod 121 is pivotally connected to a transverse pin 127 bridged between the driving levers 89 and located adjacent the pivot shaft 95 of said levers. The lower ends of the insulating rods 123 extend through the bases of the insulating columns and are pivotally connected to the ends of bell crank levers 129. A tube of insulating material 126 surrounds each rod 123 and is joined at its respective ends to the upper and lower closure members 128 and 130 as shown in Fig. 2, so as to prevent the interchange of insulating liquid between the transformer compartment in sections 17 and 19 and the interrupting compartment in section 15 of the column 11.

Provision is made for simultaneously driving the rods 123 and 121 in each column to effect simultaneous operation of the contact means of the contact assemblages in each of the two columns. Any suitable means may be provided for this purpose. In Fig. 2, a means is shown which comprises a T-shaped lever 131 pivotally mounted by means of a pin 133 on the base 1, the outer ends of the T portion being pivotally connected to the bell crank levers 129 by means of links 135, the end of the stem of the T-shaped lever 131 being pivotally connected to an operating rod 137. The operating rod 137 may be connected to any suitable type of operating mechanism either of the motor driven or solenoid operated type and by which the operating rod 137 is biased in a direction to open the breaker and is held in closed-circuit position by a suitable latching mechanism releasable by a trip means. The driving motor or solenoid provides a driving force for moving the operating rod to effect a circuit closing operation of the breaker.

The tubular casing 139 is bridged between the cap members 25 at the top of the two columns 11 and 13. The contact means of the two unitary contact assemblages 31 which are mounted in the two columns are connected in series circuit by means of a conductor which extends through the tubular bridging member 139. This conductor (not shown) is connected to a suitable flexible shunt conductor 141 carried by each of the contact assemblages 31, the lower end 143 of the flexible shunt conductor 141 being electrically connected to the contact 65 of the switch member 35.

The circuit through the breaker extends from the left hand line terminal connection 85 of the column 11 through the conducting stud 83 and the stack of circuit making and breaking units 33, through the separable contacts 63 and 65, flexible shunt conductor 141 through the conductor housed within the tubular bridging mem-

ber 139 and a conductor 141 of the contact assemblage mounted in the column 13, through the disconnecting contacts 63 and 65 and the stack of circuit making and breaking units 33 housed in said column 13 to the right hand terminal connection 85.

Disposed within the lower sections 17 and 19 of the column 11 are the windings of a current transformer 145. The current transformer is of the type which has its primary terminals at one end at line potential and its secondary terminals at the other end at ground potential. The primary winding is connected in series in the circuit between the conducting stud 83 and the line terminal 85. The secondary coil of the current transformer may be connected by its terminals 146 to suitable relays and indicating instruments as desired.

A potential transformer or voltage divider 147 is mounted within the lower sections 17 and 19 of the insulator column 13. The transformer 147 comprises a plurality of primary and secondary coil units 148, the primary coils of the units being connected between the line terminal connection 85 and ground. The secondary voltage taken from the secondary coils may be used for relaying or voltage measuring purposes.

The arrangement of the current transformer and the potential transformer within the lower sections of the insulating columns is most advantageous in that it reduces the space occupied by the breaker, requires much less insulation than was formerly used and eliminates the necessity of separate containers or tanks, together with the necessary insulating bushings therefor.

The arrangement of the current path through the circuit breaker in which the line terminal connections are positioned above, and insulated from ground by the lower sections of the insulating columns, together with the series connector 139 between the tops of the two columns which connects the contact means in each column in series, is an important feature of the invention. This arrangement of the current path provides a more equal distribution of the voltages between the series of contacts and the associated metallic parts to which the contacts are connected, in each column so that the burden of extinguishing the arc during circuit interruption is divided substantially equally between the circuit interrupting devices 33 of the two contact assemblages.

With the circuit path arranged as illustrated the capacitance of the series connector 139 with respect to ground is relatively small due to the fact that the series connector is at a greater distance from ground than are the terminals of the breaker. Assuming that a ground occurs in the load circuit, which is the worst condition obtainable, the capacitance of the series connector 139 to ground is in parallel with the series of contacts in column 15 on the load side of the breaker. If the capacitance of the series connector 139 to ground were zero, the voltage distribution between the two series of contacts in the two columns would be equal. Since this capacitance of the series connector to ground is relatively small as stated above, the voltage distribution between the two series of contacts will be substantially equal.

If the terminals 85 of the breaker were arranged at the top of the upper columns 13, and the series connector 139 at the bottom of the two columns, the capacitance of the series connector 139 to ground would be greater than in the arrangement of the present invention. With

the series connector located at the bottom of the upper columns 15 if a ground occurred in the load circuit, the capacitance of the series connector 139 to ground would be in parallel with the capacitance of the voltage dividers 147 and current transformers 145, so that the relatively large resulting capacitance to ground would be in parallel with the series of contacts in the column on the load side of the breaker. With this arrangement an unequal distribution of the voltage between the two series of contacts in the two columns 15 would result.

The upper sections 15 of each column are filled with an insulating arc extinguishing liquid to a level above the auxiliary disconnecting contacts 63-65. The spider rings 81 are provided with any suitable sealing means so that the upper sections 15 are made oil tight. The lower sections 17 and 19 of each column are also filled with an insulating liquid kept separate from the liquid in the upper sections by the aforementioned sealing means. Since the columns are of relatively small diameter, just sufficient to house the unitary contact assemblages with their stacks 25 of circuit making and breaking units, much less insulating liquid is required than in the case of metal clad circuit breakers.

The upper ends of the ring members 25 are closed by suitable closure members 151 which are removably mounted on the ring members. The feature of removably mounting the unitary contact assemblages within the interrupting sections 15 of the two columns is most advantageous in that it facilitates the servicing of the breaker.

To remove the contact assemblages, it is only necessary to remove the closure members 151 and the bolts which secure the cap members 71 to the internal flange of the ring members 25. The contact assemblages may then be withdrawn from the tubular insulating members 23 for inspection, repair or replacement purposes. The separable connection between the stack of circuit making and breaking units 33 and the line terminal connectors 85 permits removal of the contact assemblages without disconnecting any conductors.

It is believed that the operation of the circuit breaker will be readily understood from the preceding description. To close the circuit breaker, the operating rods 123 and 124 in each column are moved simultaneously in a downward direction by the operating mechanism to effect movement of the pairs of driving levers 89 of the actuating mechanisms from open to closed circuit position to effect simultaneous operation of the contact means in both columns in the manner previously described. The operating rod 137 is held in closed-circuit position by means of the latch mechanism of the operating means. When the latch mechanism is caused to release the operating rod 137 by the trip means of the operating mechanism, the biasing springs of the operating mechanism acting on said rod effects simultaneous upward movement of the insulating rods 128 and 121 in each column to cause the actuating mechanisms 97 in both columns to simultaneously open the contact means of the contact assemblages in the manner previously described.

The arrangement of the separable disconnecting contacts 63 and 65 at the top of the stacks of the circuit making and breaking units 33 provides a break in clean oil of high insulating quality and the improved actuating mechanism 75 secures a maximum travel of the switch member

which carries the movable contact 65 to provide a large gap capable of withstanding extremely high voltages to protect the circuit making and breaking devices from surges due to lightning flashes and other causes when the breaker is in the open position.

Fig. 1 illustrates a plurality of the pole units previously described mounted on a supporting frame 152 in spaced relation to form a 3 pole breaker assembly. The operating rods 137 of 10 the pole units are connected to a suitable lever mechanism indicated generally at 153 for simultaneous operation thereby so that all of the pole units are adapted for simultaneous actuation to open and close the circuits through the breaker. 15

It will be noted that in the event of breakage of any portion of the outer porcelain columns the breaker still remains operative because of the inner tubular insulating member which serves to support the unitary contact assemblage 20 and retain the insulating liquid for the same. These inner tubular members are capable of withstanding weather conditions for a limited period of time, at least until the outer tubular columns have been repaired or replaced after 25 such breakage.

While the invention has been disclosed in accordance with the provisions of the patent statutes, it is to be understood that various changes in structural details may be made therein without departing from the spirit of the invention. It is desired, therefore, that the appended claims be given the broadest reasonable construction in the light of the prior art. 30

I claim as my invention:

1. In a circuit breaker for high voltage power circuits, a substantially tubular casing of insulating material, a switch member movable to open or to closed-circuit position to open or to close the circuit through the breaker, means 40 mounting said switch member for movement within said casing in the direction of the longitudinal axis thereof, actuating means disposed in said casing for moving said switch member to open or to closed-circuit position comprising a 45 main driving lever pivotally supported adjacent one end, an intermediate multiplying lever pivotally supported adjacent one end, the free end of said main lever being pivotally coupled to said intermediate lever adjacent the pivot end thereof, a translatable lever pivoted intermediate its ends to the free end of said intermediate lever, one end of said translatable lever being pivotally connected to said switch member. 50

2. In a circuit breaker for high voltage power 55 circuits, a substantially tubular casing of insulating material, a switch member movable to open or to closed-circuit position to open or to close the circuit through the breaker, means mounting said switch member for movement within

60 said casing in the direction of the longitudinal axis thereof, actuating means disposed in said casing for moving said switch member to open or to closed-circuit position comprising a main driving lever pivotally supported adjacent one end, 65 an intermediate multiplying lever pivotally supported adjacent one end, the free end of said main lever being pivotally coupled to said intermediate lever adjacent the pivot end thereof, a third lever pivoted intermediate its ends to the 70 free end of said intermediate lever, one end of said third lever being pivotally connected to said switch member and its other end being free, said actuating means providing for maximum travel and speed of operation of said switch member 75

obtainable within the limited diameter of said casing.

3. In a circuit breaker for high voltage power circuits, a substantially tubular casing of insulating material, a switch member movable to open or to closed-circuit position to open or to close the circuit through the breaker, means mounting said switch member for movement within said casing in the direction of the longitudinal axis thereof, actuating means disposed in said casing for moving said switch member to open or to closed circuit position comprising a main driving lever pivotally supported adjacent one end, an intermediate multiplying lever pivotally supported adjacent one end, the free end of said main lever being pivotally coupled to said intermediate lever adjacent the pivot end thereof, a translatable lever pivoted intermediate its ends to the free end of said intermediate lever, one end of said translatable lever being pivotally connected to said switch member and its other end being free, guide means for the free end of said translatable lever; an operating rod extending into said casing and connected to said main driving lever for operating the same, said actuating means multiplying the travel and speed of operation of said switch member over that of said operating rod.

4. In a circuit breaker for high voltage power circuits, a substantially tubular casing of insulating material, contact means mounted in said casing including at least one pair of relatively movable contacts, a switch member movable to open or to closed-circuit position to open or close said contacts, means mounting said switch member for movement in the casing in a path substantially parallel to the longitudinal axis thereof, actuating means disposed in said casing for moving said switch member to open and to closed-circuit position comprising a lever mechanism including a translatable lever pivotally connected to said switch member, a guide for said lever; an operating rod extending into said casing for operating said lever mechanism, said contact means, switch member, and actuating means forming a unitary assemblage and means for removably mounting said assemblage in said casing.

5. In a circuit breaker for high voltage power circuits, a substantially tubular casing of insulating material; a unitary contact assemblage mounted in said casing including a plurality of pairs of relatively movable main contacts and associated arc extinguishing means, a pair of auxiliary separable contacts, the contacts being arranged in tandem and connected in series, a switch member movable substantially parallel to the longitudinal axis of the casing to open and to closed-circuit position to open and to close all of said pairs of contacts, said switch member being operable during a circuit opening operation to first effect simultaneous opening of all of said pairs of main contacts and to subsequently separate said auxiliary contacts a sufficient distance to introduce a large gap capable of withstanding high voltages, and operable during a circuit closing operation to first close said auxiliary contacts and subsequently effect simultaneous closing of all of said pairs of main contacts, and an actuating means for moving said switch member to open or to closed-circuit position comprising a straight line lever mechanism including a floating lever pivotally connected at one end to said switch member; an operating rod extending into said casing for connection with said lever mech-

anism to actuate the same, said lever mechanism multiplying the travel and speed of operation of said switch member over that of said operating rod.

6. In a circuit breaker for high voltage power circuits, a substantially tubular casing of insulating material, a unitary contact assemblage mounted in said casing including a plurality of pairs of relatively movable main contacts and associated arc extinguishing means, a pair of auxiliary separable contacts, the contacts being arranged in tandem and connected in series, a switch member movable substantially parallel to the longitudinal axis of the casing to open and to closed-circuit position to open and to close all of said pairs of contacts, said switch member being operable during a circuit-opening operation to first effect simultaneous opening of all of said pairs of main contacts and to subsequently separate said auxiliary contacts a sufficient distance to introduce a large gap capable of withstanding high voltages, and operable during a circuit closing operation to first close said auxiliary contacts and subsequently effect simultaneous closing of all of said pairs of main contacts, and an actuating means for moving said switch member to open or to closed circuit position comprising a straight line lever mechanism including a floating lever pivotally connected at one end to said switch member; an operating rod extending into said casing for connection with said lever mechanism to actuate the same, said lever mechanism multiplying the travel and speed of operation of said switch member over that of said operating rod, said casing being of limited diameter just sufficient to receive said contacts and arc extinguishing means, said lever mechanism securing maximum travel and speed of operation of said switch member obtainable within the limited diameter of said casing.

8. In a circuit breaker for high voltage power

circuits, a tubular casing of insulating material, a unitary contact assemblage disposed in said casing including a stack of circuit interrupting units each including a pair of relatively movable 5 arcing contacts, an operating member connected to said contacts for simultaneously opening and closing all of said pairs of contacts, means biasing said operating member to open said contacts, an auxiliary contact carried by said operating 10 member adjacent one end, means connecting said auxiliary contact and said arcing contacts in series, a switch member movable in a direction parallel to the longitudinal axis of the casing to open and to closed-circuit position to open and 15 to close the circuit through the breaker, said switch member being operable during a circuit closing operation to first engage said auxiliary contact and subsequently move said operating member to simultaneously close said arcing contacts, and 20 operable during a circuit opening operation to first move away from said stack to permit said operating member to simultaneously open all of said pairs of arcing contacts, and subsequently separate from said auxiliary contact to introduce a large gap capable of 25 withstanding high voltages, actuating means for moving said switch member to open and to closed-circuit position comprising a main driving lever, a floating lever pivotally connected to said switch 30 member and means connecting said driving lever to said floating lever for multiplying the travel and speed of operation of said switch member over that of said main driving lever and for maintaining a high contact pressure between said 35 contacts when the breaker is closed.

9. In a circuit breaker for high voltage power circuits, a tubular casing of insulating material, a unitary contact assemblage disposed in said casing including a stack of circuit interrupting 40 units each including a pair of relatively movable arcing contacts, an operating member connected to said contacts for simultaneously opening and closing all of said pairs of contacts, means biasing said operating member to open said contacts, an auxiliary contact carried by said operating 45 member adjacent one end, means connecting said auxiliary contact and said arcing contacts in series, a switch member movable in a direction parallel to the longitudinal axis of the casing to open and to closed-circuit position to open and to close the circuit through the breaker, said switch member being operable during a circuit closing operation to first engage said auxiliary contact and subsequently move said operating member to simultaneously close said arcing contacts, and 50 operable during a circuit opening operation to first move away from said stack to permit said operating member to simultaneously open all of said pairs of arcing contacts, and subsequently separate from said auxiliary contact to introduce a large gap capable of withstanding high voltages, 55 actuating means for moving said switch member to open and to closed circuit position comprising a main driving lever, a floating lever pivotally connected to said switch member and means connecting said driving lever to said floating lever for multiplying the travel and speed of operation of said switch member over that of said main driving lever, said unitary contact assemblage including said arcing contacts, said operating member, 60 said auxiliary contact, said switch member and said actuating mechanism being removably mounted in said casing through one end thereof.

10. A circuit breaker for high voltage power 75 circuits comprising, a supporting means, a plu-

rality of vertically arranged hollow columns mounted in spaced relation on said supporting means, a stack of interconnected circuit interrupting units disposed within the upper portion of each column, means for connecting all of 5 the units in series circuit relationship, an operating rod extending within and longitudinally of each column for actuating the interrupting units therein to open and closed positions, a common actuating means carried by said supporting 10 means and operatively coupled to the lower ends of said operating rods for simultaneously actuating said rods to open and to close the circuit through the breaker, said columns serving to insulate the circuit through the breaker from said 15 support and ground, and an insulating arc extinguishing liquid in each column.

11. A circuit breaker for high voltage power circuits comprising, a supporting means, a pair of vertically arranged hollow columns of insulating material mounted in spaced relation on said supporting means, a unitary contact assemblage disposed in the upper portion of each column including a plurality of pairs of separable main contacts and a pair of auxiliary separable disconnecting contacts arranged in tandem and connected in series, and a switch member movable to open and to closed-circuit position operable during a circuit opening operation to first simultaneously open all of said pairs of main 30 contacts to open the circuit and to subsequently open said auxiliary contacts a sufficient distance to introduce a gap capable of withstanding high voltages and operable during a circuit closing operation to close the pairs of contacts in reverse 35 order, means connecting all of the pairs of contacts in series circuit, operating means for simultaneously moving said switch members to open or to closed circuit position, and an insulating 40 arc extinguishing liquid in each column.

12. A circuit breaker for high voltage power circuits comprising a supporting means, a pair of vertically arranged hollow columns of insulating material mounted in spaced relation on said supporting means, a stack of series connected 45 circuit making and breaking units disposed in the upper portion of each column, a terminal carried by each column adjacent the base of the stack of interrupting units electrically connected to the lowermost unit thereof, a series connector bridging the tops of the two columns for connecting the interrupting units of each stack in series circuit, common operating means for simultaneously actuating the interrupting units to open and to close the circuit through the breaker, the 55 arrangement of the series connector at the top of the columns serving to more nearly equalize the voltage distribution between the interrupting units.

13. A circuit breaker for high voltage power 60 circuits comprising, a supporting means, a pair of vertically arranged hollow columns of insulating material mounted in spaced relation on said supporting means, a unitary contact assemblage disposed in the upper portion of each column including a plurality of pairs of separable main contacts and a pair of auxiliary separable disconnecting contacts arranged in tandem and connected in series, a switch member movable to open and to closed-circuit position operable during a circuit opening operation to first simultaneously open all of said pairs of main contacts to open the circuit and to subsequently open said auxiliary contacts a sufficient distance to introduce a gap capable of withstanding high voltages 75

and operable during a circuit closing operation to close the pairs of contacts in reverse order, means connecting all of the pairs of contacts in series circuit, operating means for simultaneously moving said switch members to open or to closed circuit position, an insulating arc extinguishing liquid in each column, and means for removably mounting the unitary contact assemblages in said columns.

14. A circuit breaker for high voltage power circuits comprising a supporting means, a pair of vertically arranged hollow columns of insulating material mounted in spaced relation on said supporting means, a unitary contact assemblage including a stack of series connected circuit making the breaking units and actuating means therefor disposed in the upper portion of each column, means for removably mounting the assemblages in said columns, means connecting the units in series circuit, common operating means including operating rods connected to the actuating means of each stack for simultaneously actuating the units to open and to close the circuit through the breaker, at least one of said operating rods extending axially within one of said hollow columns, and an insulating arc extinguishing liquid in each column.

15. A circuit breaker for high voltage power circuits comprising a supporting means, a pair of vertically disposed hollow columns of insulating material mounted in spaced relation on said supporting means, a unitary contact assemblage including a stack of series connected circuit making and breaking units, and actuating means therefor disposed in the upper portion of each column, a terminal carried by each column adjacent the base of the stack connected to the lowermost unit thereof, a series connector bridging the tops of the columns including a conductor for connecting the circuit making and breaking units of the two stacks in series circuit, operating means including an insulating rod extending into each column for connection with the actuating means for simultaneously actuating the units to open or to close the circuit through the breaker.

16. A circuit breaker for high voltage power circuits comprising a supporting means, a pair of vertically disposed hollow columns of insulating material mounted in spaced relation on said supporting means, a unitary contact assemblage including a stack of series connected circuit making and breaking units and actuating means therefor disposed in the upper portion of each column, a terminal carried by each column adjacent the base of the stack connected to the lowermost unit thereof, a series connector bridging the tops of the columns including a conductor for connecting the circuit making and breaking units of the two stacks in series circuit, operating means including an insulating rod extending into each column for connection with the actuating means for simultaneously actuating the units to open or to close the circuit through the breaker, and an insulating arc extinguishing liquid in each column.

17. A circuit breaker for high voltage power circuits comprising a supporting means, a pair of vertically disposed hollow columns of insulating material mounted in spaced relation on said supporting means, a unitary contact assemblage including a stack of series connected circuit making and breaking units and actuating means therefor disposed in the upper portion of each column, a terminal carried by each column adjacent the base of the stack connected to the lower-

most unit thereof, a series connector bridging the tops of the columns including a conductor for connecting the circuit making and breaking units of the two stacks in series circuit, operating means including an insulating rod extending into each column for connection with the actuating means and a common actuating mechanism carried by said support means and operatively coupled to the lower ends of said insulating rods for simultaneously actuating the units to open or to close the circuit through the breaker.

18. A circuit breaker for high voltage power circuits comprising a supporting means, a pair of vertically disposed hollow columns of insulating material mounted in spaced relation on said supporting means, a unitary contact assemblage including a stack of series connected circuit making and breaking units and actuating means therefor disposed in the upper portion of each column, a terminal carried by each column adjacent the base of the stack connected to the lowermost unit thereof, a series connector bridging the tops of the columns including a conductor for connecting the circuit making and breaking units of the two stacks in series circuit, operating means including an insulating rod extending into each column for connection with the actuating means for simultaneously actuating the units to open or to close the circuit through the breaker, and means for removably mounting said contact assemblages in the upper portions of said columns.

19. In a circuit breaker, a movable switch member for opening and closing the circuit, actuating mechanism for moving the switch member to open and to closed circuit position including a translatable lever pivotally connected at one end to said switch member, having its other end free of any connection and connected intermediate its ends to said actuating mechanism for movement thereby, and support means forming a temporary fulcrum for the free end of said translatable lever during a portion of its movement.

20. In a circuit breaker, a movable switch member for opening and closing the circuit, actuating mechanism for moving the switch member to open and to close the circuit, said mechanism including a lever movable by said mechanism and having one point thereon pivotally connected to said switch member and a second point thereon free of any connection, a guide means forming a temporary fulcrum for the second point on said lever during a portion of its movement.

21. In a circuit breaker, a movable switch member for opening and closing the circuit, means mounting said switch member for movement in a substantially straight line path, actuating mechanism for moving said switch member to open and to closed circuit position comprising an actuating member movable in an arcuate path, a translatable lever pivotally connected intermediate its ends to said actuating member for movement thereby and having one end pivotally connected to said switch member, guide means for the opposite end of said lever, said mechanism being operable during a closing operation to move said lever from a position transverse to the path of movement of said switch member to a position substantially parallel to the path of movement of said switch member to effect movement of the switch member to closed circuit position.

22. In a circuit breaker, a movable switch member for opening and closing the circuit, means mounting said switch member for movement in a substantially straight line path to an

- open and to a closed circuit position, actuating mechanism for moving said switch member to open and to closed circuit position including a translatable lever pivotally connected to said mechanism for movement thereby and also pivotally connected to said switch member, said mechanism being operable during a closing operation to cause movement of said lever from one position to a substantially inverted position in which it is substantially in line with the path of movement of said switch member.
23. In a circuit breaker, a movable switch member for opening and closing the circuit, means mounting said switch member for movement in a substantially straight line path, actuating mechanism for moving said switch member to open and to closed position comprising a translatable lever pivotally connected intermediate its ends to said mechanism for movement thereby and having one end pivotally connected to said switch member, guide means engageable by the other end of said lever during a portion of its movement, said mechanism being operable during a closing operation to cause said lever to translate and rotate from a position in which it makes an acute angle with the path of movement of said switch member to a substantially inverted position in which it is substantially in line with said path of movement to effect movement of the switch member to closed position.
24. In a circuit breaker, a movable switch member for opening and closing the circuit, actuating mechanism for moving the switch member to open and to close the circuit, said mechanism including a lever movable by said mechanism and having one point thereon pivotally connected to said switch member and a second point thereon free of any connection, a guide means forming a temporary fulcrum for the second point on said lever during a portion of its movement, a movable operating member for operating said actuating mechanism, said actuating mechanism multiplying the travel and speed of operation of said switch member over that of said operating member.
25. In a circuit breaker, a substantially tubular casing of relatively small diameter, a switch member in said casing movable in the direction of the longitudinal axis of said casing for opening and closing the circuit, actuating mechanism in said casing for moving said switch member to open and to closed position, said mechanism including a translatable lever movable by said mechanism having one point pivoted to said switch member and a second point free of any connection, guide means forming a temporary fulcrum for the second point on said lever during a portion of its movement, said mechanism being operable during a closing operation to cause said lever to fulcrum on said guide means and translate to a position substantially parallel to the longitudinal axis of said casing.
26. In a circuit breaker, a movable switch member for opening and closing the circuit actuating mechanism for moving said switch member to open and to closed circuit position, including a translatable lever pivotally connected at one end to said switch member and movable by said mechanism, said mechanism being operable to effect translating movement of said lever and rotation thereof through an angle greater than 90° to effect movement of the switch member.
27. In a circuit breaker, a movable switch

member for opening and closing the circuit, means mounting said switch member for movement in a substantially straight line path, actuating mechanism for moving said switch member to open and to closed circuit position comprising an actuating member movable in an arcuate path, a translatable lever pivotally connected intermediate its ends to said actuating member for movement thereby, and having one end pivotally connected to said switch member, guide means for the opposite end of said lever, said mechanism being operable during a closing operation to move said lever from a position transverse to the path of movement of said switch member to a position substantially parallel to the path of movement of said switch member to effect movement of the switch member to closed circuit position, an operating member for operating said actuating mechanism, said actuating mechanism multiplying the travel and speed of operation of said switch member over that of said operating member.

28. In a circuit breaker for high voltage power circuits, a casing, a switch member movable to open and closed positions to open and close the circuit through the breaker, means mounting said switch member for movement within said casing, actuating means disposed in said casing for moving said switch member to open and closed positions comprising a main driving lever pivotally supported adjacent one end, an intermediate multiplying lever pivotally supported adjacent one end, the free end of said main lever being pivotally coupled to said intermediate lever adjacent the pivoted end thereof, and a translatable lever pivoted intermediate its ends to the free end of the intermediate lever, one end of said translatable lever being pivotally connected to said switch member.

29. In a circuit breaker, a hollow column of insulating material, means closing the ends of said column, means dividing said column into circuit interrupting and transformer chambers, insulating liquid in each of said chambers, circuit interrupting means disposed within said interrupting chamber, actuating means within said column for operating said interrupting means to open and closed positions, said actuating means including an operating rod extending through said transformer chamber and operatively coupled with said interrupting means, and tubular means surrounding said operating rod and joining the respective ends of said transformer chamber to prevent the intermingling of liquid between said chambers.

30. In a circuit interrupter, a housing comprising a pair of tubular sections of insulating material, a metallic casing disposed between said sections, closures for the opposite ends of said sections and a partition wall within said casing dividing said housing into circuit interrupting and transformer chambers, insulating liquid within each of said chambers, circuit interrupting means including a movable contact carrying member disposed within said circuit interrupting chamber operating means in said casing for actuating said contact carrying member to open and closed positions, an operating rod extending through said transformer chamber for actuating said operating means, and tubular means surrounding said operating rod and joining the respective ends of said transformer chamber to prevent the intermingling of liquid between said chambers.
